UNITED STATES PATENT OFFICE.

ARTHUR R. EARNSHAW, OF WYNNEWOOD, PENNSYLVANIA, ASSIGNOR TO EARNSHAW MANUFACTURING CORPORATION, OF PHILADELPHIA, PENNSYLVANIA, A CORPORATION OF DELAWARE.

REFRIGERATING SYSTEM.

Application filed August 14, 1922. Serial No. 581,569.

This invention relates to refrigerating apparatus intended particularly for domestic use, and an object of the invention is to simplify apparatus of this type by reducing to 5 a minimum the number of controlling devices necessary, and to provide a simple and automatic means whereby operation of the apparatus may take place without constant attention or the necessity of frequent adjustment.

Another object of the invention is to provide a refrigerating system which shall operate at all times at the highest point of efficiency. This is accomplished in the present invention by virtue of the particular design of the apparatus and the proportion and relation of the several parts whereby the entire amount of active refrigerant in the system is maintained at all times in the 20 zone of refrigeration.

Another object of the invention is to provide a simple and efficient refrigerating apparatus, of the character set forth, with an automatic float valve which is uninfluenced 25 by pressure variations and designed to provide a check between the compressor and cooling coil to permit the building of pressure for condensation of the gaseous refrigerant; to permit the refrigerant as fast as it 30 is liquefied under pressure to automatically pass into the cooling coil, and to prevent the entrance into the latter of any of the gaseous refrigerant.

A still further object of the invention is 35 to provide a novel form of pressure controlled switch for starting and stopping the compressor motor forming part of my system, and means to control the temperature of the system through pressure variations 40 acting upon the switch actuating mechanism.

In addition to the foregoing, this invention comprehends improvements in the details of construction and arrangement of the correlated parts to be hereinafter set forth 45 and particularly pointed out in the appended claims.

In the accompanying drawings, Fig. I is 50 a view illustrating diagrammatically the elements of my improved refrigerating apparatus in assembled relation.

Fig. II is a view in section of the float valve.

Fig. III is a detail view in section of a

fragment of a slightly modified form of float valve.

Fig. IV is a view of the float in top plan and its connection to the valve; and

Fig. V is a view in side elevation of my improved pressure controlled switch.

With reference to the drawings, 10 indicates a compressor and 11 a directly coupled prime mover such as an electric motor, a cooling fan 12 being mounted upon the coupling shaft connecting the elements. The compressor 10 and motor 11 are mounted upon a base 13, upon which rests an inverted channel casing 14 enclosing the elements and constituting an air-tunnel through which air is caused to flow by rotation of the fan 12 so as to carry away the heat generated during operation. The condensing coil indicated at 15 is also enclosed within the casing 14 and is connected in the usual manner to the discharge port of the compressor 10 and to the liquor line 16 which, in the present instance, is led upward toward the refrigerator 17, entering the top wall of the same and extending downward into the cooling compartment 18 provided therein for the reception of the cooling portion of the refrigerating 20 circuit.

The liquor line 16 is connected at its terminal to the upper portion of a float casing 19, shown in detail in Fig. II and having one side open and threaded internally 25 to receive a plug 20 permitting access to the mechanism within the casing 19 for adjustment when occasion requires. An outlet port 21 is provided in the casing 19, and located in the latter for communication with 30 said port is a valve casing 22 having a horizontal valve seat in which a plug 23 is rotatably held. A stem 24 extends laterally from the plug 23 and supports a float 25. The plug 23 is provided with a transverse 35 passage 26 which is adapted to register with a passage 27 extending through the valve casing 22 when the float 25 is in an elevated position. In addition thereto a by-pass 28 is provided in the bottom wall of the float 40 casing 19, affording communication between the interior of the latter and the discharge port 21 for shunting the valve 22. A hand operated valve 29 is interposed in said by-pass and is normally adjusted to closed position.

The upper end of an evaporating element or cooling coil 30 is in communication with the discharge port 21 while the lower end of said cooling coil extends into a reservoir 31 having a cavity 32 provided in its upper portion in which pans of water may be received when making ice. The evaporating element may be the coil 30, a chamber or any enclosure adapted to receive the liquor and permit evaporation thereof for the purpose of effecting refrigeration. The float casing 19, it will be noted is located at the lower end of the cooling coil 30. The return or gas line indicated at 33 is connected to the upper portion of the reservoir 31 and is extended upward through the top wall of the refrigerator 17 and then to the intake port of the compressor 10. The liquor line 16 and the gas line 33 are preferably brought into close relation at a point within the cooling compartment 18 of the refrigerator 17 and this may be accomplished in several ways as for instance by wrapping the liquor line 16 around the gas line 33 in the form of a coil whereby heat interchange may take place between the two lines. If the compressor 10 and condenser 15 are located above the zone of refrigeration the coiling of the liquor and gas lines 16, 33 respectively may be avoided, as the drop is then direct.

The gas line 33 is tapped at a point adjacent the compressor 10 to provide a branch 34 which is extended to an automatic pressure controlling device indicated comprehensively at 35 and operatively associated with a switch for controlling the feeding of the motor 11 so that the compressor 10 may be started or stopped automatically in accordance with variations in pressure in the gas line 33, which are consistent with variations in temperature in the cooling apparatus.

Any suitable type of pressure controlled switch may be employed but I have found the form illustrated in the accompanying drawings to be efficient and well adapted for the purpose besides having several advantages inherent to itself in the way of regulation. In detail, and referring more particularly to Fig. V, the switch 35 consists of a hollow expansible element 36 having its interior established in communication with the branch 34 by means of a coupling connection 37. The element 36 is supported at one end upon a standard 38 while its opposite end is free to move axially by expansion or contraction of said element, the movable end being provided with a rod 39 which slides freely in a standard 40. A pair of nut and jam nut couplers 41 and 42 are threaded upon the rod and located at opposite sides of the standard 40. A pair of coiled springs 43 and 44 are encircled about the rod 39, the former being interposed be-

tween the nut couple 41 and standard 40 and the latter between said standard and the nut couple 42. The switch proper indicated at 45 may be of any type including an oscillatory finger 46 which is pivotally connected to the end of the rod 39 the latter having a turnbuckle 47 interposed between aligned sections of said rod so that the effective length of the latter may be varied for the purpose of adjusting the stroke of the rod 39 to the throw of the switch finger 46.

It will be apparent that by adjusting the nut couples 41 and 42 the tension of the springs 43 and 44 may be placed in such relation that the switch finger 46 may be thrown at any predetermined rise or fall of pressure in the gas line 33, and that the pressure variation possible between maximum pressure limits of switch throw-off and thrown-on may be altered to vary the sensitivity of the system to temperature changes. The expansible element 36 is practically independent of atmospheric pressure by reason of the springs 43, 44, the tension of which primarily control the degree of expansion and contraction of said element 36.

It will be noted that the float valve 22 constitutes a check in the liquor line 16 permitting the building of pressure in the condenser 15 so that the liquefaction of the gaseous refrigerant may be aided and ensured. The active refrigerant, and by that I mean liquid refrigerant, flows through the liquor line 16 and into the float casing 19. As the float 25 rises under the buoyant influence of the liquor sufficient to open the valve 22 the refrigerant flows into the cooling coil 30 until by drainage of the liquor said float 25 falls below a predetermined point causing the valve 22 to again close, thus preventing the passage of any gaseous refrigerant into the cooling coil 30. It will be noted at this point that the operation of the float 25 is not affected in any degree by pressure or pressure variations in the system but its operation is affected solely by the presence or absence of liquid in the casing 19.

The active refrigerant flows through the cooling coil 30 and accumulates in the reservoir 31, absorbing heat from surrounding parts or the air in the refrigerator resulting in the corresponding evaporation of the active refrigerant, the gaseous refrigerant passing through the line 33 back to the compressor. The reservoir 31 is initially filled to a point slightly below its top wall or below the mouth of the gas line 33 with liquid refrigerant so that said reservoir is never quite full even when containing all of the active refrigerant in the system. Consequently there is no possibility of any of the liquid refrigerant entering the gas line 33.

The formation of a gas lock in the float casing 19 is prevented to a great extent by the close relation of the liquor and gas lines 16, 33 respectively permitting of heat inter-
5 change at a point closely adjacent the float casing 19. However, should a gas lock occur the accumulated liquid refrigerant and gas causing the lock may be passed into the cooling coil 30 by manually opening the by-
10 pass valve 29. If desired however the bypass 28 may be omitted from the valve structure.

Owing to the fact that the float valve 25 forms an absolute control over the supply 15 of active refrigerant to the coil, it will be seen that the cooling coil 30 and reservoir 31 are continually supplied at all times with a maximum amount of active refrigerant and that the remaining part of the circuit with 20 the exception of the liquor line 16 and condenser 15 contains gaseous refrigerant only, the gaseous refrigerant fed to the condensing coil 15 being quickly reduced to liquid state and immediately supplied to the float 25 casing 19. The float valve 25 being automatic in its action, the entire apparatus, particularly in view of the automatic pressure control 35 operates continually without 30 attention and ensures a uniform degree of refrigeration which may be predetermined by preadjustment of the pressure controlling device 35 in the manner stated. The opening of the valve 22 may be made large enough to prevent the possibility of clogging so that 35 the feeding through of liquid is graduated by the angle of rise of the float 25 and is greater or less as the supply varies. As the operation of the valve 22 is not influenced by pressure variations the float 25 and 40 casing 19 may be small and compact. As no evaporation takes place in the float valve casing 19, there is no chilling of oil that may be present and consequently no clogging of the valve 22.

45 A slightly modified construction of the valve casing 22 is shown in Fig. III, wherein said valve casing is provided with a reduced extension 36 which enters an opening in the bottom wall of the float casing 19 and is formed with a threaded terminal 50 which enters the port 21 so that a nut 37 may be applied to said terminal and turned tightly against a washer interposed between said nut and the wall of the port, a similar 55 washer being interposed between the inner wall of the casing 19 and the shoulder formed by the reduction of the terminal 36. This type of valve casing permits of a more ready assembly of the parts.

Having thus described my invention, I 60 claim:

1. In an automatic refrigerating apparatus including a circulatory system, a prime mover under automatic governance of a pressure controlled switch, a compressor, a 65 fan and a condenser all housed as a unit within an open-ended casing constituting an air tunnel, in combination with an exposed cooling coil, a casing interposed between the condenser and cooling coil, located adjacent the lower end of the latter, in communication with the upper end of said coil, a reservoir below the coil in communication with the lower end thereof, and a float valve pivoted in said casing permitting 70 the passage of accumulated liquid refrigerant into the cooling coil but preventing the passage of gaseous refrigerant.

2. In an automatic refrigerating apparatus including a circulatory system, a prime 80 mover under automatic governance of a pressure controlled switch, a compressor, a fan and a condenser all housed as a unit within an open-ended casing constituting an air-tunnel, in combination with an exposed 85 cooling coil, a reservoir fed directly by the cooling coil of a capacity to contain all of the liquid refrigerant in the system, a pivotally mounted float valve interposed in the liquor line adjacent the reservoir and cooling 90 coil to permit the passage of accumulated liquid refrigerant directly into said cooling coil but to prevent the passage of gaseous refrigerant, and a gas return connection leading from the reservoir to the compressor. 95

3. In an automatic refrigerating apparatus including a circulatory system, a prime mover under automatic governance of a pressure controlled switch, a compressor, a fan and a condenser all housed as a unit within 100 an open-ended casing constituting an air-tunnel, a liquor line supplied by the condenser, a casing connected to said liquor line to receive liquid refrigerant, an exposed cooling coil supplied from said casing, a 105 float valve in said casing permitting the passage of liquid refrigerant to the cooling coil but preventing the passage of gaseous refrigerant, a subjacent reservoir supplied by said coil, and a gas return line leading from the 110 reservoir to the compressor, the liquor line being intimately associated with the gas line by coiling thereabout at a point adjacent the valve casing.

In testimony whereof, I have hereunto 115 signed my name at Philadelphia, Pennsylvania, this seventh day of August, 1922.

ARTHUR R. EARNSHAW.
